UNITED STATES PATENT OFFICE.

FRANK A. LUNDQUIST, OF NEW YORK, N. Y., ASSIGNOR TO WESTERN ELECTRIC COMPANY, INCORPORATED, OF NEW YORK, N. Y., A CORPORATION OF NEW YORK.

AUTOMATIC SWITCH.

1,273,247.

Specification of Letters Patent.

Patented July 23, 1918.

Application filed December 2, 1916. Serial No. 134,577.

To all whom it may concern:

Be it known that I, FRANK A. LUNDQUIST, a citizen of the United States, residing at New York, in the county of New York and State of New York, have invented certain new and useful Improvements in Automatic Switches, of which the following is a full, clear, concise, and exact description.

This invention relates to selecting switches and more particularly to automatic switches employed in telephone systems.

This invention has for its purpose the production of an automatic switch which is economical to manufacture, rapid in operation and whose contacting elements are compactly arranged.

One feature of this invention is the novel arrangement of the fixed or passive terminals of a group of lines.

Another feature of this invention is the production of an automatic switch in which the movable brushes are actuated by gravity to bring them into engagement with the terminals of the selected line.

Still another feature of the invention resides in the manner in which the flexible cord conductors, usually employed to connect to the movable terminals or brushes, are eliminated.

Other features of the invention will appear from the following detailed description and claims.

Referring to the drawings, Figure 1 represents a skeleton side view of the switch with certain parts broken away and also shows a circuit arrangement suitable for operating the switch. Fig. 2 is a plan view of the switch, showing the arrangement of the fixed contacts or terminals and the arrangement of the movable terminals or brushes of the switch. Fig. 3 shows a side elevation of the terminal bank and the arrangement of a set of brushes for engagement with the fixed contacts or terminals of the bank.

The switch consists of a terminal bank of the panel type, which consists of a plurality of contact strips separated by suitable insulating material, and of directly controlled sets of movable brushes operated by gravity. In the restoration of the switch a power-driven shaft elevates the brushes to their normal positions.

5 designates a brush shaft mounted for vertical and rotary movement in a frame

(not shown). This shaft 5 carries sets of movable terminals or brushes 7, which are spaced apart and spirally arranged on the shaft. The sets of movable brushes 7 are arranged to engage the fixed terminals of a 60 terminal bank generally designated as 9.

The terminal bank 9 is of the panel type and consists of strips of conducting material each separated by suitable insulation, and clamped in fixed relation to each other 65 in any suitable support. The conducting strips arranged in sets of three are provided with contacts which constitute the tip, ring and sleeve contacts of any line. The numerals 13 and 15 designate the tip and ring 70 contacts and numeral 14 designates the sleeve or test contact of the set. By reference to Figs. 2 and 3 it will be seen that the tip and ring contacts 13 and 15 are shorter than test contact 14 and are offset at right angles 75 thereto but the general arrangement of the contacts 13, 14 and 15 is in a vertical row. Parallel to and adjacent each group of contacts there are placed conducting or commutator strips 16 and 17 with which the 80 movable brushes 18 and 19 engage when they are in engagement with any set of fixed contacts. The brushes 10 and 11 are insulatedly mounted on shaft 5 and engage the offset ends of contacts 13 and 15 respectively, 85 while the test brush 20 in set 7, which is not insulated from shaft 5, engages the ends of the test contacts 14.

The brush shaft 5 near its intermediate portion is provided with rotary ratchet teeth 90 21 with which the rotary pawl 22 engages to rotate the shaft. The pawl 22 is secured to the arm of the bell crank lever 23. This lever is pivoted to the frame and is actuated by armature 24 of the rotary magnet 25. 95 An insulated projection 26 which is carried by the bell crank lever 23 controls the contact springs 27. A holding dog 28 normally engages the rotary ratchet teeth 21 to hold the shaft in the position to which it has 100 been rotated. A second bell crank lever 29 mounted on the frame is controlled by a lug 30 on the rotary pawl 22 to disengage the holding dog 28 from the rotary ratchet teeth 21 while the shaft is being rotated. 105 The holding dog 28 near its upper portion has an angular projection 31 which engages an insulating disk 32 carried by the shaft to hold the dog out of engagement with the rotary ratchet teeth 21 during the restora- 110

tion of the switch to its normal position. The insulating disk 32 also controls a set of contact springs 33 and 34 as will be hereinafter described. Near the upper portion 5 of the brush shaft there is mounted for rotary movement on the shaft 5, a double tooth ratchet 35. An escapement member 36 carried on an arm of the frame engages with the teeth of the ratchet member 35. The escapement member 36 is provided with an arm 37, which is arranged to be engaged by a projection on a pivoted latch member 38. This latch member is controlled by the armature of the relay 39 and operates to lock 10 the escapement 36 and during the setting of the switch operates to close circuits through the contacts 40 and 41. A constantly rotating shaft 42 is supported in any suitable manner on the frame of the switch. A 15 spring actuated clutch member 43 is normally held out of the clutch member 71 by means of a bell crank lever 44. The clutch 43 carries a drum 44 on which a cord 46 secured to the shaft 5 is wound during the 20 restoration of the switch. The bell crank lever 44, which is pivoted to the frame terminates in a transverse hook 48, while its other end terminates in an upturned portion 49. An additional bell crank lever 25 50 also pivoted to the frame is actuated by the armature of magnet 51. This lever 50 is provided with insulated knob 52 which controls the closing of contact springs 53 and is further provided with the latch member 30 54 to engage the hook 48 and a resilient catch 55 which engages the lug 56 of the shaft for purposes to be hereinafter described.

In the operation of the switch when the 40 subscriber, whose substation apparatus is designated as 57, removes his receiver from the hook, a line finder indicated by the brushes 58 and 60 operates to connect a calling substation to the selector switch of this 45 invention. As soon as the finder has found the terminals of the calling line a circuit is completed from grounded battery, winding of relay 59, upper side of the line, finder brush 58, substation apparatus 57, the finder brush 60 of the finder switch, winding of the relay 61, to ground. The relay 59 retracts its armature for each interruption of its energizing circuit but the relay 61, however, is slow to release, or in other words, 50 55 its armature does not retract during momentary interruptions of its operating circuit. When the circuit, just described, is completed through the winding of these relays they attract their armatures. When, 60 however, the subscriber operates his dial switch, relay 59 vibrates its armature and thereby completes a circuit from grounded battery, armature and back contact of the relay 59, inner armature and front contact 65 of relay 61, contact springs 33, winding of

the relay 25, to ground. The relay 25 vibrates its armature in response to the impulses transmitted by the subscriber. Armature 24 actuates the bell crank lever 23 causing the member 29 to disengage the holding dog 28 from the rotary ratchet teeth and simultaneously causing the pawl 22 to engage the rotary ratchet teeth 21 to rotate the shaft. The shaft 5 is rotated under the control of the rotary magnet 25 until the proper set of brushes 7 has been placed in operative relation to the selected group of trunks. When the rotary magnet 25 first operated its armature 24 the insulated projection 26 brought the contact springs 27 into engagement to close a circuit from grounded battery through the contact springs 27, winding of the slow releasing relay 62, to ground. The relay 62 attracts its armature to prevent the energization of magnet 39 at this 70 time. It will be understood that the insulated projection 63, carried by the shaft, disengages the spring 64 after the first rotary step of the shaft. This permits the contact spring 64 to engage the contacts 65 80 and 66. At the close of the directive series of impulses the energizing circuit of the relay 62 is opened at the contact springs 27 causing the relay 62 to retract its armature. A circuit is thereupon closed from grounded battery, winding of the relay 39, contact springs 34, armature and back contact of the relay 62, contact 66, contact spring 64, contact 65, to ground. The relay 39 attracts 85 its armature thereby disengaging the latch 90 member 38 from the arm 37 of the escapement 36. As soon as the shaft descends this circuit is interrupted at contact springs 34, but another energizing circuit for relay 39 is completed from grounded battery, winding 95 of relay 39, insulated contact 40, latch member 38, conductor 67, test brush 12, test contacts of busy trunks to ground through the test brush of other switches, through conductors similar to 67, through 100 latch members and contacts similar to 38 and 40, to ground. The shaft 5 descends under the control of the escapement member 36 until the test brush 20 encounters the test terminal of an idle trunk. This idle condition of the trunk is indicated by the absence 105 of ground on its test terminal. As soon as the test brush 20 encounters the test terminal characterized by the absence of ground, the magnet 39 retracts its armature causing the 110 latch member 38 to engage the arm 37 of the escapement 36 to hold the shaft in the position to which it has been lowered. As soon as the armature of the relay 39 is retracted 115 a ground is applied to the test terminal of the trunk seized, over a circuit extending from ground, insulated contact 40, latch member 38, conductor 67, test brush 20 to the test terminal 14. The calling substation 120 125 130 135 57 is extended to the succeeding selector

through finder brushes 58 and 60, trunks 72 and 73, conducting strips 17 and 16 respectively, brushes 19 and 18, terminals 13 and 15 and trunk conductors 74 and 75.

5 At the termination of the conversation when the subscriber replaces his receiver on the switchhook the energizing circuit of the relays 59 and 61 is interrupted causing these relays to retract their armatures. A circuit 10 is then completed from grounded battery, outer armature and back contact of the relay 61, winding of the magnet 51, contact springs 64, contact 65, to ground. The magnet 51 attracts its armature and disengages 15 latch 54 from the transverse hook 48, which permits the bell crank lever 44 to disengage the clutch member 43. The clutch member 43 then engages the member 71, winding the cord 46 on the drum 45. The shaft 5 is 20 thus elevated until the spring catch 55 engages the lug 56 to support the shaft in its elevated position. It will be noted that as soon as the magnet 51 attracts its armature a circuit is closed from grounded battery, 25 winding of magnet 39, through contact springs 53, to ground. The relay 39 is energized in this circuit and attracts its armature, thereby disengaging the latch member 38 from the arm 37 of the escapement member. While the shaft 5 is being elevated 30 to the position just described the insulating disk 32 encounters arm 31, to disengage the holding dog 28 from the rotary ratchet teeth 31. As soon as this takes place coil spring 35 68 causes gear wheels 69 and 70 to rotate the shaft to its normal rotary position. When the shaft rotates to normal the insulated knob 63 opens the energizing circuit of relay 51 which is completed through contact 40 spring 64 and contact 65. The relay 51 retracts its armature, thereby causing the spring catch 55 to disengage lug 56 of the shaft. Simultaneously the latch 54 engages the hook 48 which causes lever 44 to force 45 clutch member 43 out of engagement with member 71. The switch is now in its normal position.

What is claimed is:

1. In a terminal bank, a plurality of contact strips insulatively separated from each other, contacts on said strips extending from the face of said bank, contacting portions of certain of said contacts being in a plane parallel to the face of the bank, contacting portions of certain others of said contacts being in a plane which intersects the face of the bank, and means for supporting said contact strips in fixed relation.
2. In a terminal bank, a plurality of contact strips insulatively separated from each other, contacts on said strips, the ends of

certain of said contacts being arranged to serve as the contacting portions, and the sides of other of said contacts being arranged to serve as the contacting portions, 65 and means for supporting said contact strips in fixed relation.

3. In a terminal bank, a plurality of contact strips insulatively separated from each other and arranged in sets, contacts on said 70 sets of strips arranged in alinement, contacting portions on the sets of said contacts being diagonally arranged, and means for supporting said contact strips in fixed relation. 75

4. In a terminal bank, a plurality of insulatively separated contact strips, said contact strips being arranged in sets, contacts on said strips, certain of the contacts of a set having contacting portions extending in a 80 direction at right angles to the contacts, and means for supporting said contact strips in fixed relation.

5. In an automatic switch, passive contacts, a brush support, a set of brushes secured to said support and mounted to engage said passive contacts, said brushes having contacting surfaces, the contacting surface of one of said brushes of a set extending in a different direction from the contacting 90 surfaces of other brushes of the set, means to operate said brush support, and means to release the same. 85

6. In an automatic switch, passive contacts arranged in sets, each contact of the 95 set having a contacting portion which extends in a different direction from the contacting portions of other contacts of the set, a brush support, a set of brushes secured to said support and arranged to engage said 100 sets of contacts, said brushes having contacting portions, the contacting surface of one of said brushes of a set extending in a direction at right angles to the contacting surfaces of other brushes of the set, means 105 to operate said brush support, and means for releasing the same.

7. In a terminal bank, a plurality of contact strips insulatively separated from each other and arranged in sets, contacts on said 110 strips arranged in alinement, the ends of certain of the contacts in alinement being arranged to serve as the contacting portion, the sides of other of the contacts in alinement being arranged to serve as the 115 contacting portion, and means for supporting said contact strips in fixed relation.

In witness whereof, I hereunto subscribe my name this 29th day of November, A. D. 1916.

FRANK A. LUNDQUIST.
